JOHN MARIAN, OF HARTFORD, CONNECTICUT.

AUTOMATIC FEED FOR PUNCH PRESSES.

1,407,699.

Specification of Letters Patent. Patented Feb. 28, 1922.

Application filed April 9, 1921. Serial No. 460,058.

To all whom it may concern:

Be it known that I, JOHN MARIAN, a citizen of Czernowitz, Bukowina, formerly a part of the Empire of Austria-Hungary, but 5 now a part of the State of Rumania, and a prospective citizen of the United States, residing at Hartford, in the county of Hartford and State of Connecticut, have invented a new and useful Improvement in Automatic Feeds for Punch Presses, of which the 10 following is a specification.

This invention relates to those mechanisms which are designed to be applied to punch presses for automatically feeding strips of 15 stock beneath the cutting punch by the downward movement of the ram that carries the punch.

The object of the invention is to provide a 20 mechanism of this class which is simple and cheap to construct, which can be readily applied to most of the common types of punch presses and which can be adjusted so as to accurately feed the required distance strips of 25 indefinite length and any width and thickness within the range of the particular mechanism.

In the accompanying drawings Fig. 1 shows a plan of a mechanism which embodies the invention. Fig. 2 shows a side elevation 30 of the same. Fig. 3 shows an end elevation of the mechanism. Fig. 4 is a transverse section on the plane indicated by the dotted line 4—4 on Fig. 2. Fig. 5 is a view looking toward the feed jaws carried by the slide 35 which is advanced for feeding the stock on the downward stroke of the ram.

The body 1 is a casting that is adapted to be bolted to the table of the press with which the mechanism is to be used.

40 Fastened to the front face of the body is a track plate 2 with a V shaped groove in its upper edge. The slide 3 which is arranged to be reciprocated along the front face of the body above the track plate has a 45 V shaped groove in its lower edge. Anti-friction balls 4 are placed in the grooves between the track plate and slide for supporting the latter and a retaining plate 5 is fastened to the slide for keeping the balls 50 properly spaced. A clamped plate 6 which is fastened to the top of the body reaches over the top edge of the slide for keeping the slide in position on the track. A spring 7 located in a socket in the end of the slide 55 and having one end connected with the slide

and the other end connected with a pin 8 projecting from the body, draws the slide back. On the front end of the slide is a hardened plate 9.

For moving the slide forward there is a 60 lever 10 that is pivoted to the body and at its upper end has a rearwardly extended pin 11 carrying a roller 12 which is adapted to be engaged by the ram or other movable part of the press to which the mechanism is applied. The lever desirably has several pivot holes 13 so that its active length can be varied when necessary. A link 14 connects the lever and the slide. At its upper end the link is pivotally fastened to the lever, and at 65 its lower end the link is yieldably and adjustably, pivotally connected with the slide. The lower end of the link has a transverse slot and longitudinal socket, a bolt 15 extending through the slot with its head 16 lying in a 70 T shaped mortise in the front face of the slide. On the bolt is a sleeve 17 and secured to the outer end of the bolt is a nut 18. When the nut is loosened the position of the bolt along the slide may be changed for 75 varying the pivotal point of connection of the link with the slide. A block 19 is arranged in the slot to bear against the sleeve on the bolt and a spring 20 is located in the socket so as to thrust against the block and 80 normally keep the pivot bolt in the lower end of the slot. On the lower corner of the link is a roll 21 that is designed to run on the upper edge of a guide plate 22 which is adjustably fastened by bolts 23 to the front of 85 the body.

The slide at its rear raised end carries a square bar 24 and adjustably fastened on this bar is a downwardly extending arm 25. Secured to this arm, so that it may be adjusted 90 up and down, is a plate 26 pivoted upon which are a pair of toothed feed jaws 27. These jaws are eccentrically mounted and springs 28 are arranged to turn them toward each other. The feed jaws are so mounted 100 that when the slide is retracted they will slide over the strip of stock which extends between them, but when the slide is forced forward the jaws will close upon the stock and feed it.

The body at its raised front end carries a square bar 29 and adjustably secured to this bar is a downwardly extending arm 30; fastened on this arm so that it may be adjusted 105 up and down is a plate 31 pivoted upon 110

which are a pair of toothed eccentrically mounted stock holding jaws 32 normally closed by springs 33. The holding jaws are similar to and are mounted the same as the feeding jaws and they close upon and hold the stock when the feeding jaws are retracted for more stock. Any desired number of arms carrying jaws may be located upon the bars which project from the slide and from the body. The jaws are raised up and down to carry the stock at the required level and they are adjusted on the bar toward the front and back, so that the stock will be in the proper line.

15 Facing the hardened plate on the front end of the slide is a stop screw 34 which is turned through a threaded opening in the boss 35 forming a part of the body for engaging the plate and stopping the slide when it has fed the stock into exact position. The guide plate 22 is located so that when the slide is feeding stock the roll 21 will run upon the upper edge of the plate but when the stock has been properly fed and the slide is stopped by the stop screw, the roll will run down the inclined end 36 of the plate and the spring in the end of the link will yield so that the parts will not become damaged by the continued downward movement of the ram after the stock has been stopped in the exact position and the punch descends further for piercing the stock.

The invention claimed is:

1. An automatic feed for attachment to punch presses comprising a body, a track plate fastened to the front face of the body, a slide movable along said track, means for retaining the slide on the track against the body, a spring for retracting the slide, a lever pivoted to the body and provided with means adapted to be engaged by a part of the press to which the mechanism is to be applied, a link pivoted to the lever and yieldably and adjustably connected with the slide, a pair of feed jaws carried by said slide, and a pair of holding jaws mounted on the body.

2. An automatic feed for attachment to punch presses comprising a body, a track plate fastened to the front face of the body, a slide movable along said track, means for retaining the slide on the track against the body, a spring for retracting the slide, a lever pivoted to the body and provided with means adapted to be engaged by a part of the press to which the mechanism is to be applied, a link pivoted to the lever and yieldably and adjustably connected with the slide, a screw turning in the body for stopping the feed of the slide, a pair of feed jaws carried by said slide, and a pair of holding jaws mounted on the body.

3. An automatic feed for attachment to punch presses comprising a body, a track plate fastened to the front face of the body,

a slide movable along said track, means for retaining the slide on the track against the body, a spring for retracting the slide, a lever pivoted to the body and provided with means adapted to be engaged by a part of the press to which the mechanism is to be applied, a link pivoted to the lever, a bolt adjustably connected with the slide, said link being yieldably connected with the slide, a pair of feed jaws carried by said slide and a pair of holding jaws mounted on the body.

4. An automatic feed for attachment to punch presses comprising a body, a track plate fastened to the front face of the body, a slide movable along said track, means for retaining the slide on the track against the body, a spring for retracting the slide, a lever pivoted to the body and provided with means adapted to be engaged by a part of the press to which the mechanism is to be applied, a link pivoted to the lever and yieldably and adjustably connected with the slide, bars extending rearwardly from the slide and body and vertically and horizontally adjustable feed and holding jaws supported by said bars.

5. An automatic feed for attachment to punch presses comprising a body, a track plate fastened to the front face of the body, a slide movable along said track, a spring for retracting the slide, a lever pivoted to the body and provided with a roller that is adapted to be engaged by a part of the press to which the mechanism is to be applied, a link pivoted to the lever and yieldably and adjustably connected with the slide, a bar extending rearwardly from the slide, an arm extending downwardly from said bar, a pair of feed jaws mounted on said arm, a bar extending rearwardly from the body, an arm extending downwardly from said bar, and a pair of holding jaws mounted on said arm.

6. An automatic feed for attachment to punch presses comprising a body, a track plate fastened to the front face of the body, a slide movable along said track, a spring for retracting the slide, a lever pivoted to the body and provided with a roller that is adapted to be engaged by a part of the press to which the mechanism is to be applied, a link pivoted to the lever and yieldably and adjustably connected with the slide, a bar extending rearwardly from the slide, an arm extending downwardly from said bar, a plate vertically adjustable on said arm, and a pair of feed jaws pivotally mounted on said plate.

7. An automatic feed for attachment to punch presses comprising a body, a track plate fastened to the front face of the body, a slide movable along said track, a clamp plate for retaining the slide on the track against the body, a spring for retracting the slide, a lever pivoted to the body and pro-

vided with a roller that is adapted to be engaged by a part of the press to which the mechanism is to be applied, a link pivoted to the lever and yieldably and adjustably connected with the slide, a bar extending rearwardly from the slide, an arm extending downwardly from said bar, a plate vertically adjustable on said arm, and a pair of feed jaws pivotally mounted on said plate.

10 8. An automatic feed for attachment to punch presses comprising a body, a track plate fastened to the front face of the body, a slide movable along said track, a clamp plate for retaining the slide on the track 15 against the body, anti-friction balls arranged between the track and slide, a spring for retracting the slide, a lever pivoted to the body and provided with a roller that is adapted to be engaged by a part of the press 20 to which the mechanism is to be applied, a link pivoted to the lever and yieldably and adjustably connected with the slide, a bar extending rearwardly from the slide, an arm extending downwardly from said bar, a plate vertically 25 adjustable on said arm and a pair of feed jaws pivotally mounted on said plate.

9. An automatic feed for attachment to punch presses comprising a body, a track 30 plate fastened to the front face of the body, a slide movable along said track, a clamp plate for retaining the slide on the track against the body, anti-friction balls 35 arranged between the track and slide, a plate fastened to the slide for retaining the balls in position, a spring for retracting the slide, a lever pivoted to the body and provided with a roller that is adapted to be engaged by a part of the press to which the mechanism 40 is to be applied, a link pivoted to the lever and yieldably and adjustably connected with the slide, a bar extending rearwardly from the slide, an arm extending downwardly from said bar, a plate vertically 45 adjustable on said arm and a pair of feed jaws pivotally mounted on said plate.

10. An automatic feed for attachment to punch presses comprising a body, a track plate fastened to the front face of the body, 50 a slide movable along said track, a clamp plate for retaining the slide on the track against the body, anti-friction balls arranged between the track and slide, a plate fastened to the slide for retaining the balls 55 in position, a spring for retracting the slide, a lever pivoted to the body and provided with a roller that is adapted to be engaged by a part of the press to which the mechanism is to be applied, a link pivoted to the

lever and yieldably and adjustably connected with the slide, a bar extending rearwardly from the slide, an arm extending downwardly from said bar, a plate vertically adjustable on said arm, a pair of feed jaws pivotally mounted on said plate, and a set screw turning through the body into the path of the slide.

11. An automatic feed for attachment to punch presses comprising a body, a track plate fastened to the front face of the body, 70 a slide movable along said track, a clamp plate for retaining the slide on the track against the body, anti-friction balls arranged between the track and slide, a plate fastened to the slide for retaining the balls 75 in position, a spring for retracting the slide, a lever pivoted to the body and provided with a roller that is adapted to be engaged by a part of the press to which the mechanism is to be applied, a link pivoted to the 80 lever and yieldably and adjustably connected with the slide, a guide plate for the lower end of the link adjustably fastened to the face of the body, a bar extending rearwardly from the slide, an arm extending 85 downwardly from said bar, a plate vertically adjustable on said arm, a pair of feed jaws pivotally mounted on said plate, and a set screw turning through the body into the path of the slide.

12. An automatic feed for attachment to punch presses comprising a body, a track plate fastened to the front face of the body, 90 a slide movable along said track, a clamp plate for retaining the slide on the track 95 against the body, anti-friction balls arranged between the track and slide, a plate fastened to the slide for retaining the balls in position, a spring for retracting the slide, a lever pivoted to the body and provided with a roller that is adapted to be engaged by a part of the press to which the mechanism is to be applied, a link pivoted to the lever and yieldably and adjustably connected with the slide, a guide plate for the 100 lower end of the link adjustably fastened to the face of the body, a bar extending rearwardly from the slide, an arm extending downwardly from said bar, a plate vertically 105 adjustable on said arm, a pair of feed jaws pivotally mounted on said plate, a bar extending rearwardly from the body, an arm extending downwardly from said bar, a plate vertically 110 adjustable on said arm, a pair of jaws pivotally mounted on said plate, and a set screw turning through the 115 body into the path of the slide.

JOHN MARIAN.
